UNITED STATES PATENT OFFICE.

FREDERICK R. HOARD, OF PROVIDENCE, RHODE ISLAND.

HAND-BAG AND THE LIKE.

1,172,768.

Specification of Letters Patent. Patented Feb. 22, 1916.

Application filed May 12, 1915. Serial No. 27,553.

To all whom it may concern:

Be it known that I, FREDERICK R. HOARD, a citizen of the United States, residing at Providence, in the county of Providence and 5 State of Rhode Island, have invented a new and useful Improvement in Hand-Bags and the like, of which the following is a specification.

This invention relates to certain new and 10 useful improvements in hand bags and the like, and pertains more particularly to the body construction of bags of the general type indicated.

The primary object of the invention is to 15 provide a structure of bag in which great strength, longevity and wearing qualities are possessed, while at the same time not adding to the weight of the bag.

A further object of the invention is to 20 provide a bag in which a fine mesh wire cloth is utilized as the base of the bag body structure, enabling the inside of the bag, as well as the outside, to be finished in varying manners, and with different finishing materials, such for instance as leather, paper, 25 canvas or straw, or other materials.

In the drawings—Figure 1 is a side elevation of the bag, partly broken away and in section. Fig. 2 is a section on the line 2—2 30 of Fig. 1, and Fig. 3 is a similar view on the line 3—3 of Fig. 1.

In proceeding in accordance with the present invention, the body of the bag structure is formed of fine wire mesh fabric 1 35 which is shaped to conform to the outline which the bag is to possess. The bag body may be formed from a single piece of material 1, or it may be formed of separate pieces connected and shaped to conform to 40 the outline which the bag is to have. Secured to the outside of the wire fabric 1 is the finishing material 2 which latter may be canvas, leather, or leather imitation, paper, canvas, straw or any other suitable material 45 suitable for the purpose, which material may be waterproofed, if desired. Similarly finishing material 3 may be secured to the interior of the fabric 1, and may be of any desired character, such as canvas, leather,

silk or other textile fabric, paper, chamois, 50 or straw.

One of the important advantages which the invention possesses is that of enabling the finishing materials, whether inside or outside or both, to be sewed to the mesh fabric, by 55 reason of the foraminous character of the latter, allowing the needle to be easily moved through the interstices, as will be obvious. This advantage is no less important however, than that which also follows in cases where 60 glue, waterproof cement, or other adhesives are used to secure the finishing materials in lieu of stitching, namely, the interstices, allow the glue to pass therethrough and thus 65 firmly connect the material to the fabric, and in cases where both inside and outside finishing materials are employed, the glue will act to connect both *i. e.*, by extending through the interstices of the fabric and contacting with both the inside and outside materials. 70

A further important advantage of the invention is that the mesh fabric, due to its resilient nature tends to always open the sides of the bag at the mouth thereof so that upon release of the usual catch or lock, the 75 mouth of the bag is sprung open, so to speak. In addition the usual reinforcing pieces P and the usual mouth finishing plates M can be easily and effectively connected by stitching or riveting to the fabric and will be 80 securely held against being pulled off, or disengaged, which latter is common to leather bags formed of thin material. The wire fabric also reinforces the bag body structure, and imparts strength and maximum wearing 85 property thereto.

Having thus described my invention, what I claim as new and desire to secure by Letters Patent is—

As a new article of manufacture, a bag 90 composed of a body formed of fine metal wire mesh, inner and outer finishing facings engaged with the mesh, and unitary fastening means to rigidly and permanently secure the facings to the wire mesh so that the wire 95 mesh and both facings form a unitary structure, said fastening means extending through the meshes of the wire so as to

rigidly and simultaneously connect the facings to opposite sides of the wire mesh, said body being so shaped that the mesh also acts to cause the body at the mouth thereof to spring open and remain open when the mouth is unfastened.

In testimony whereof I have signed my

name to this specification in the presence of two subscribing witnesses.

FREDERICK R. HOARD.
